UNITED STATES PATENT OFFICE

CHARLES FERGUSON, OF ELLIS ISLAND, NEW YORK

VENTILATING APPARATUS

Application filed May 8, 1929. Serial No. 361,355.

This invention relates to new and useful improvements in ventilating apparatuses, and aims to provide a relatively simple and inexpensive means for use in the home, factory, theatre or the like, whereby to provide within the building proper ventilation.

Furthermore, the invention aims to provide a device of this character wherein the air being projected therethrough will in one instance be thoroughly purified, and in another instance, a modification of the main idea, be thoroughly purified and dried. In both instances, the air is also cooled to a relatively high degree, so as to maintain the interior of the building in a relatively cool state during the warm weather.

An important object of the invention is to provide a ventilating apparatus for use in the home or for use, on a slightly larger scale, within a theatre, office building or the like, of a generally inexpensive nature, and that is highly efficient in attaining the desired results.

In the drawings wherein there is disclosed two embodiments of the present invention:

Figure 1 is a detailed longitudinal section view through one type of the invention that is preferably used in the home.

Figure 2 is a horizontal section taken at right angles to Figure 1.

Figure 3 is an enlarged fragmentary longitudinal section through the absorbent disk carrying unit that forms an essential feature of the invention.

Figure 4 is a detailed longitudinal section through a ventilating apparatus constructed in accordance with the present invention, and of a type preferably employed on a large scale, that is, within theatres, office buildings and the like.

Figure 5 is a view partially in end elevation and partially in cross section through that type of the apparatus disclosed in Figure 4, and

Figure 6 is an enlarged fragmentary section through the air drying chamber of this type of the invention.

First having reference to Figures 1, 2 and 3, the form of the invention illustrated there-

the front and rear wall of which are provided with relatively large circular openings 6-6, while the top thereof is provided with a hinge lid 7, in order that access may be had to the housing. Arranged within the bottom of this housing is a water pan 8 at one end of which is arranged a water tank 9, having a suitable filler neck 10 projecting through an opening in the hinged lid of the housing as illustrated in Figure 2. The lower end of this tank is equipped with a discharge nozzle 11, the outlet end of which is arranged within the water pan 8, so that a steady flow of water will be introduced into the pan for maintaining a permanent level thereof, as illustrated in Figure 2.

Within the housing 5 between the tank 9 and the opposite end wall thereof are a pair of spaced shaft supporting brackets 12-12 adapted to loosely support the opposite ends 70 of a horizontal shaft 13. Mounted upon this shaft 13 at spaced points are disks of absorbent material such as blotting paper 14 maintained in spaced relation by suitable spacing collars 15. Intermediate the disks of absorbent material are disks of wire mesh screening 16 which are also arranged upon the shaft and function as a supporting means to prevent excessive sagging or lateral bending of the absorbent discs when the same are 80 saturated with water.

The diameter of the disks 14 and 16 are such that they will always engage at their lower ends within the water within the pan 8, as illustrated in Figures 1 and 2. Furthermore, these disks are free to rotate upon the shaft 13 as suggested by the curved arrow in Figure 1.

Arranged at the back side of the housing 7 is a fan housing 17, the fan blade unit 18 of 90 which is located directly in back of the circular opening in the rear wall of the housing, so that the air being discharged forwardly by the fan will pass through the housing 5, as disclosed by the horizontal arrows in Figure 4. During the passage of the air through the housing 5, it will come into contact with the absorbent disks 14, as well as the screen wire disks 16. This will thoroughly remove from the air all impurities, and will at the same 100

time cool the same to a considerable degree. In the form of the invention illustrated in Figures 4, 5 and 6, the same general construction is present. In this instance however, the housing 5' is of considerable length, and is provided throughout its length with a series of vertical partitions 6', the lower edges of which are spaced from the bottom wall of the housing, and which are provided with large circular openings 6a. At the opposite ends of this housing 5' are relatively narrow compartments or chambers 17'-17'. The various compartments of the housing 5', as well as the outer endmost chamber 17' are provided with hinged lids as clearly illustrated so that access may be had therein. Within the bottom of the housing 5' is arranged a water pan 8', while arranged transversely within each of the compartments of the housing are screen and absorbent disk material units designated in their entirety by the reference characters 14'. These units are of identical construction as the unit in the previously described form of the invention, and a detailed description thereof is not believed necessary.

Within the outer end compartment 17' are a plurality of spaced baffle plates 19 alternate ones of which are in spaced relation with the upper and lower walls of the chamber, as disclosed in Figure 4. These baffle plates are covered by a suitable moisture gathering material 20, as disclosed in Figure 6, while within the bottom of this chamber is a moisture collecting pan 21.

Within the rear end chamber 17 of the device is located a suitable fan or blower 22, projecting air through the compartments of the housing, as well as through the moisture removing chamber or compartment 17', and obviously during the passage of the air through the compartments of the main housing, the air will be thoroughly purified and cooled, while when passing through the moisture absorbing chamber, all moisture within the air will be collected, so that the air when finally leaving the apparatus will be of a thoroughly cleaned, cooled and dried nature.

In view of the foregoing description when considered in conjunction with the accompanying drawings, it will be apparent that I have provided a novel, simple and highly efficient ventilating apparatus, in each modification of the invention, and even though I have herein shown and described the two modifications as consisting of certain detailed structural features, it is nevertheless to be understood that some changes may be made therein, without affecting the spirit and scope of the appended claim.

Having thus described my invention, what I claim as new, and desire to secure by Letters-Patent, is:

In a ventilating apparatus of the character described, a housing having air passages at

its opposite ends, a fan at one end thereof for driving air through the housing, a transversely extending shaft mounted for rotation in the housing, a series of absorbent discs mounted on the shaft in spaced relation, means for supplying water to the absorbent discs and a series of foraminous discs mounted on the shaft intermediate the absorbent discs and in spaced relation thereto, said foraminous discs constituting lateral supporting means for preventing excessive sagging or bending of the absorbent discs after the latter are saturated with water.

In testimony whereof I affix my signature.

CHARLES FERGUSON.
